(57) **CLAIM**

We claim the ornamental design for a portion of a biochemical analyzer, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, top and right side perspective view of a portion of a biochemical analyzer showing our new design, and the drawing shows features of the invention in the color blue;

FIG. 2 is a front elevational view thereof, and the drawing shows features of the invention in the color blue;

FIG. 3 is a rear elevational view thereof, and the drawing shows features of the invention in the color blue;

FIG. 4 is a left side elevational view thereof;

FIG. 5 is a right side elevational view thereof, the drawing showing features of the invention in the color blue;

FIG. 6 is a top plan view thereof, and the drawing shows features of the invention in the color blue;

FIG. 7 is a bottom plan view thereof;

FIG. 8 is a cross sectional view taken along the lines 8-8 of FIG. 5, and the drawing shows features of the invention in the color blue; and,

FIG. 9 is a reference front, top and right side perspective view thereof shown in an opened position, and the drawing shows features of the invention in the color blue.

The broken lines shown are for illustrative purposes only and form no part of the claimed design.
